UNITED STATES PATENT OFFICE.

MORTIMER L. SWEENEY, OF NEW YORK, N. Y., ASSIGNOR OF ONE-HALF TO CHARLES H. TREAT, OF NEW YORK, N. Y.

TELEGRAPH OR CABLE CODE.

933,679.

Specification of Letters Patent. Patented Sept. 7, 1909.

Application filed April 10, 1909. Serial No. 489,236.

To all whom it may concern:

Be it known that I, MORTIMER L. SWEENEY, a citizen of the United States, residing at New York, in the county of New York and

5 State of New York, have invented certain new and useful Improvements in Telegraph or Cable Codes, of which the following is a specification.

10 My invention relates to an improved cable or telegraph code, the primary object of which is to produce a code by which the tolls for the transmission of messages will be materially reduced.

15 A further object of my invention is to produce a code which can be made of a size sufficient to cover all possible phrases which may be desired, and by my invention approximately seventy-five thousand code words are provided and this without duplicating any

20 code word.

With these and other objects in view my invention consists in forming a code made up from words of two, three and four letters each, the words of two letters being arranged in one set or table, the words of three letters being arranged in a second set or table, and the words of four letters being arranged in a third set or table. These two, three and four letter words are adapted to

25 be joined together to form pronounceable words of nine letters or less, and I also provide an index or key which consists of one or more letters adapted to be added to such compound word to indicate the particular combination of tables which has been employed to form the word to be transmitted.

Under the present international rules of the cable and telegraph companies any pronounceable word of ten letters or less may be

40 transmitted as a single word. Consequently under my system it is possible to send a plurality of code words joined together for which the toll for but a single word will be charged.

45 Referring to the drawings wherein I illustrate portions of the pages of a code constructed according to my system, Figures 1, 2 and 3 indicate sections of the three tables formed of the two, three and four letter words respectively; Figs. 4, 5 and 6 indicate sections of the key or index by which the

50 particular combination of code words is indicated; Fig. 7 illustrates a message comprising three code words taken from the various tables with the indicator at the end

thereof, the same being joined together so as to be transmitted as a single word, and also showing a translation of such transmitted word.

As illustrated in the drawings, Table No. 1 60 is made up entirely of code words of two letters. Table No. 2 is made up entirely of words of three letters, and Table No. 3 is made up entirely of words of four letters. By employing all the two, three and four 65 letter combinations approximately seventy-five thousand different code words can be obtained, and this number is more than sufficient for all purposes. In the formation of the word to be transmitted these two, three 70 and four letter code words will be joined together in various combinations, so that it is necessary, in order to properly divide the transmitted word into its component code words to have an indicator which will give 75 the necessary information as to the number of letters in each code word of the transmitted word, to enable the transmitted word to be properly divided. This information is given by the use of the letters which are 80 added at the end of the transmitted word. Consequently each transmitted word ends in a letter which will indicate what particular combination of code words has been used to make up the transmitted word. 85

In the example given in Fig. 7 the table indicator is the letter *a*. Upon reference to the section of the index shown in Fig. 4 it is discovered that the first code word is taken from Table No. 1, the second code word from 90 Table No. 2, and the last code word from Table No. 3. Consequently the transmitted word is to be divided into three words, the first containing two letters, the second three letters and the third four letters. When the 95 transmitted word has been so divided into the three code words each is looked up in its appropriate table and translated.

If all the code words are taken from a single table then one of the indicators illustrated in Fig. 5 is placed at the end of the composite or transmitted word, or if the word is made entirely from two tables one of the indicators shown in Fig. No. 6 is added 100 to the composite word. 105

From the above description it will be seen that a transmitted word may contain four code words, and the index letter if they are all taken from Table No. 1, or three of them taken from Table No. 1, and one from Table 110

No. 2. Three code words if all of them are taken from Table No. 2, or one from each table, or two from Table No. 2, and one from Table No. 1, and transmitted as a single word as each of these furnishes a word to be transmitted of ten letters or less, after the addition of the indicator at the end of the word.

Without enumerating the equivalents and without setting forth all the forms which my 10 invention may take, what I claim as new and desire to secure by Letters Patent is:

1. A code which consists of two, three and four letter words, each of which has a predetermined meaning, said words being adapted 15 to be combined into a pronounceable word and transmitted as a single word, and indicators adapted to be used with said two, three and four letter words to indicate the division of the transmitted word into the 20 proper code words.

2. A code which consists of a plurality of tables one of said tables being composed of code words each containing one number of letters and another table composed of code 25 words containing a different number of let-

ters, said code words being adapted to be combined into a pronounceable word and transmitted as a single word, and indicators adapted to be added to a word formed by the combination of code words from said tables 30 to indicate the division of the entire word into its component code words.

3. A code which consists of three tables, one of said tables comprising a series of two letter code words, the second table comprising 35 a series of three letter code words and the third table a series of four letter code words, said code words being adapted to be combined into a pronounceable word and transmitted as a single word, and a series of indicators which may be added to a word formed from a combination of code words from the 40 various tables to indicate the particular combination which has been formed.

In testimony whereof I affix my signature 45 in presence of two witnesses.

MORTIMER L. SWEENEY.
